UNITED STATES PATENT OFFICE.

JASPER BLACKBURN, OF WEBSTER GROVES, AND ARTHUR ALBRECHT, OF ST. LOUIS, MISSOURI; SAID ARTHUR ALBRECHT ASSIGNOR TO SAID JASPER BLACKBURN.

METHOD OF GALVANIZING.

Application filed December 7, 1925. Serial No. 73,558.

Our invention relates to improvements in method of and apparatus for galvanizing, and has for its primary object the method of galvanizing, which is commercially known as the hot dip process in which a number of articles are simultaneously treated in the molten metal and then plunging them into a cooling bath and during such plunging treating the same so that all blisters and roughness due to cooling are eliminated.

A still further object is the construction of an apparatus for galvanizing by means of which the finished articles are first placed in a pickling solution for the purpose of removing all scale, oil, rust and other impurities, then dipping the same in a galvanizing solution, and lastly cooling the same in such a manner that the formation of blisters and rough spots is eliminated and a smooth job results.

In the drawings:

Fig. 1 is a view of the galvanizing tank employed in carrying out our invention;

Fig. 2 is an enlarged section of the cooling vat taken on the line 2—2 of Fig. 4; and

Fig. 3 is a perspective view illustrating the manner of assembling a number of articles to be galvanized;

Fig. 4 is an end view of dipping tank employed; and

Fig. 5 is an elevation of the several pickling tanks; and

Fig. 6 is a top plan view of galvanizing tank.

In the construction of our device, we employ a number of pickling vats 4. This may be either in the form of crocks or they may be of any desired shape. 5 represents a heating furnace of any desired type in which is located a tank 6. This tank is designed to contain spelter or other material used in galvanizing. The furnace 5 is preferably provided with a shelf 7, the purpose of which will be explained later. Mounted on the furnace 5 is a fuel pipe 8 through which gas or similar fuel is passed. This pipe is provided with branch pipes 9, which terminate in burners or jet tips 10. These tips are above the tank 6 and face each other so that the flames issuing from these tips will be projected toward each other and across the top of the tank 6. Connected to each of the tips 10 is an air pipe 11, which pipes are connected to a single pipe 12. This pipe has a valve 13 which is designed to be opened by

means of a foot lever 14. A spring 15 is employed to raise the foot lever 14 and close the valve. Secured to the valve 13 is a pipe 16, which leads to any suitable source of air supply. Located at a distance from the furnace 5 is a cooling tank 17, which has located therein a plate 18. This plate is preferably arranged at an angle as illustrated in Fig. 2. Located in the tank is a body of water 19 on which floats a body or layer of oil 20. 21 represents a plurality of articles to be galvanized and 22 the loop or wire by means of which the articles are secured together.

The method of utilizing the apparatus is as follows:

A number of articles are strung on a wire loop 22. These articles, which will be termed bundles hereafter, are then placed in the pickling vats which contain a solution for cleansing the articles. The spelter or other galvanizing material is placed in the tank 6 and heat supplied thereto from the furnace 5 so as to melt the same. The oil and water are also preferably heated but not sufficiently to cause either of them to boil.

After the pickling has been completed and the galvanizing material melted in the tank, the fuel supply is turned on and ignited as it issues from the tips 10.

The device is now ready for operation. An operator takes a hook and removes one of the bundles from the pickling vat and places it on the shelf 7. An operator standing on the opposite side of the furnace 5 now picks up the bundle with another hook and dips it into the molten metal, leaving it immersed for a short period of time. The bundle is then raised out of the metal and the operator depresses the pedal or lever 14, opening the valve 13 and causing a jet of air to mingle with the fuel passing through the tips 10. This causes an intensely hot flame to issue from each of these tips and play around the bundle, heating the same and at the same time causing the metal to become more fluid. Certain parts of this metal drip off and back into the vat. The operator then removes his foot from the pedal 14 shutting off the air supply, and swinging round strikes the bundle against the plate 18, thus imparting a jar to the bundle and separating any articles which may have become stuck together. The bundle is then lowered and passes through

the layer of oil and by a continued movement down into the water after which it is withdrawn and placed in a suitable location where the remainder of the cooling can take place. We have found by this method that a much smoother job results because by cooling with oil in this manner the tendency of the material to blister and present a roughened surface is eliminated.

10 While we have shown and described our device as utilizing oil on top of water, this can be varied by using oil entirely but the oil and water makes the cost of our operation considerably less because it is not necessary to use such a large quantity of oil, and the results obtained in either case are the same.

Having fully described our invention, what we claim is:—

20 1. The method of galvanizing which comprises first pickling the article to be treated for a predetermined length of time, second dipping the same in a bath of molten metal, third suspending the article in a flame for

raising its temperature and removing surplus bath metal therefrom, and lastly passing it through a layer of oil and into a body of water by a continuous movement for cooling the same.

2. The method of galvanizing which comprises first making a bundle of a number of articles to be treated, second pickling said bundle, third dipping said bundle into a bath of molten metal, fourth removing said bundle from said bath and simultaneously therewith subjecting the same to a flame for increasing its temperature, fifth jarring said articles so as to separate the same from each other, sixth passing said bundles through oil and into water by a continuous movement for cooling and setting the metal adhering to the articles.

3. The method of galvanizing of claim 1 in which the oil and water are heated.

In testimony whereof we have affixed our signatures.

JASPER BLACKBURN.
ARTHUR ALBRECHT.
